UNITED STATES PATENT OFFICE.

SAMUEL J. SHERER, OF CHICAGO, ILLINOIS.

DISPLAY DEVICE.

SPECIFICATION forming part of Letters Patent No. 780,070, dated January 17, 1905.

Application filed May 18, 1904. Serial No. 208,511.

To all whom it may concern:

Be it known that I, SAMUEL J. SHERER, a citizen of the United States, residing at Chicago, in the county of Cook and State of Illinois, have invented a certain new and useful Improvement in Display Devices, of which the following is a specification.

My invention relates to devices for displaying material, and has for its object to provide new forms and constructions for devices of that class.

I have illustrated my invention in the accompanying drawings, wherein—

Figure 1 is a plan view of one form of my invention; Fig. 2, a like view of a modification. Fig. 3 is a plan view of a single tray such as is shown in Fig. 1. Fig. 4 shows the tray illustrated in Fig. 3 in its inverted position. Fig. 5 is a section on line 5-5 of Fig. 3.

Like letters of reference indicate like parts in all the drawings.

A A are trays for holding the material displayed and are preferably somewhat shallow, having the retaining edges B B. These trays may be made from sheets of metal or any suitable material. The edges B may be integral with the bottom part and turned up so as to retain the material.

C C are raised letters in the trays A A. These may be struck up from the bottom of the trays, as shown in Fig. 5, this construction making it possible to use the device with the trays inverted, as shown in Fig. 4. The letters, however, may or may not be of the same material. Fig. 1 shows a series of such trays arranged so that the letters spell the word "Oolong." In Fig. 2 I have shown a single tray, which may be constructed in the same manner, having a series of raised letters, in this case spelling the word "Florida." The form of device shown in Fig. 4 is precisely the same as the other devices, but is inverted.

I have shown and described the raised and recessed portions of the display-receptacles as made in the form of letters; but it will be apparent that I might give them the configuration of any character, symbol, or device, and in drawing the claims I use the word "character" in this broad signification.

The pans or trays should have substantially

the same depth as the characters, so that when either the space about the characters or the characters themselves are filled with the material to be displayed the raised surface of the pan or the character, as the case may be, shall be in approximately the same plane as the surface of the material. The space in the pan about that character should be such as to present sufficient volume to receive suitable quantities of the material to be displayed.

I have thus described my device as I prefer to construct it; but it will be clear that the forms and constructions above set forth might be greatly varied without departing from the spirit of my invention, and consequently I do not limit myself to the particular forms and devices set out.

The use and operation of my invention is as follows: As shown in Fig. 1, the trays are filled with the material displayed, which in this case is tea, and are placed side by side. The raised letters will obviously protrude through the material, and the trays may be arranged to spell the word desired. As shown in Fig. 4, a tray may be inverted, and in this event the material is displayed in the recessed letter or other character. Thus, for example, all of the trays shown in Fig. 1 might be so arranged, or part one way and part the other.

It will be clear that the trays or receptacles might be considerably changed in form and might be adapted to contain and display almost any sort of material without departing from the scope of my invention.

I claim—

1. A display device comprising a receptacle for material having a raised character therein.
2. A display device comprising a tray, having a raised character struck up from the bottom thereof.
3. A display device comprising a reversible receptacle having a raised character on one side and a recessed character on the other side.
4. A reversible display device comprising a tray having a raised character struck up from the bottom thereof, in such a manner as to provide a recessed receptacle of similar form when the device is inverted.
5. A display device comprising a series of display-receptacles having raised characters

therein, and being adapted to be arranged so as to present a word or symbol in the material displayed.

6. A display device comprising a series of 5 reversible display-receptacles having hollow raised characters on one side and corresponding recesses on the other side, and adapted to be arranged either side up, so as to contain and display material, and at the same time to 10 display a word or symbol.

7. A display device comprising a body por-

tion with a character-shaped portion and a recess associated therewith so as to outline such character-shaped portion and adapted to receive material to be displayed, the whole arranged so that the exposed surface of the material to be displayed will lie in substantially the same plane. ¹⁵
